APPARATUS FOR TESTING AND DISPLAYING THE BOILING POINT OF BRAKE FLUID

Irwin E. Fuchs and Leon Kresser, St. Louis, Mo., assignors to The Bardahl Oil Company, Inc., St. Louis, Mo., a corporation of Missouri

Application January 10, 1955, Serial No. 33,904

Term of patent 7 years

(Cl. D16—2)

FIG. 1.

FIG. 2.

FIG. 3.

Fig. 1 is a top plan view of an apparatus for testing and displaying the boiling point of brake fluid, showing our new design;

Fig. 2 is a front elevational view thereof, and

Fig. 3 is a side elevational view thereof.

We claim:

The ornamental design for an apparatus for testing and displaying the boiling point of brake fluid, substantially as shown.
